RADIO TRANSMITTING SYSTEM

Application filed January 13, 1930. Serial No. 420,312.

This invention relates to high frequency carrier wave telegraph transmitting systems and particularly to short wave radio transmitters.

5 An object of the invention is to secure constancy in the frequency of the carrier wave generated in such a system.

Regulation of the frequency of radio transmitters has been a serious, practical problem 10 for many years, particularly in short wave transmitters where the frequencies of different channels differ by an extremely small percentage although the differences as expressed in terms of wave-lengths or cycles may be 15 relatively great. Frequency drift occurs particularly as a transient condition following the starting of oscillations in a vacuum tube oscillator and is therefore especially annoying in radio telegraph transmitters in which 20 keying is accomplished by starting and stopping the oscillator.

It has been discovered that heating, and 25 consequent expansion, of the grid is one of the chief causes of transient frequency drift, in accordance with this invention such drift is reduced by maintaining the grid of the tube at a uniform temperature at all times regardless of whether or not it is oscillating. This uniform grid temperature is maintained 30 by applying to the grid during non-signaling intervals a current which has the same heating effect thereon as the oscillatory current generated when the key is closed.

The invention will now be described in detail with the aid of the accompanying drawing in which:

Figs. 1, 2, and 3 are schematic circuits showing three alternative methods of heating the grid of a vacuum tube during non-signaling intervals.

In Fig. 1, a vacuum tube 1, having a cathode 2, grid 3 and anode 4, has a frequency determining, tuned output circuit comprising a variable condenser 14 and inductance 15.

45 The inductance 15 is coupled to an inductance

16 connected to a transmitting antenna 17. The lower terminals of the tuning condenser 14 and inductance 15 are connected to the cathode 2 through a by-pass condenser 13. Anode potential for the tube is supplied from a battery or other source of potential 25 50 through contacts of relay 20, and radio frequency choke coil 19. Relay 20 is connected in the keying circuit, which includes battery 24 and lower contacts 22 of key 23.

The input, or cathode-grid circuit of the tube 1 comprises an inductance 50 and a radio frequency by-pass condenser 5 in series between the cathode and grid. In a circuit of this type sufficient energy is transferred from the output circuit to the input circuit through the grid-anode capacity of the tube to produce continuous oscillations, at short wave-lengths. Shunted across condenser 5 is a source of low frequency current comprising the secondary winding 8 of a transformer 7, 60 the primary winding 9 of which may be connected through contacts 27 and 28 of a relay 26, with a source of alternating current 41. Source 41 may supply 110 volts at 60 cycles, 65 and the transformer 7 may have such a ratio as to step this voltage up to a value between 500 and 1,000 volts, the exact value required being determined by the characteristics of the tube and the conditions under which it 70 is operated. The secondary voltage may be varied within limits by adjusting a rheostat 10 in the primary circuit. To prevent high potentials of radio frequency from being impressed on the windings of transformer 7, by-pass condensers 6 and 42 may be shunted 75 across the secondary winding and between the primary and secondary terminals, respectively, as shown.

In operation, the tube 1 is energized to produce radio frequency oscillations by pressing key 23, which closes the circuit between battery 24 and relay 20, causing the latter to operate and connect the anode battery 25 between the cathode and anode of the oscillator 80 85 90

tube. When the tube 1 is oscillating, the grid 3 becomes alternately positive and negative with respect to the cathode 2, and during intervals when the grid is positive it attracts electrons from the cathode, causing a flow of rectified current in the grid circuit which, together with the radio-frequency current, is sufficient to heat and expand the grid. This expansion, in the case of a short wave oscillator, may change the cathode-grid capacity sufficiently to produce an objectionable shift in the frequency of oscillation. To produce a compensating heating effect on the grid when tube 1 is not oscillating, upper contact 21 is provided on the key 23 which closes a circuit to energize relay 26, at the same time relay 20 is released. Relay 26, in operating, closes contacts 27 and 28, which connect the source of 60 cycle alternating current 41, to primary winding 9 of transformer 7. The resultant alternating voltage induced in winding 8 of transformer 7 is applied between the grid and cathode of the oscillator tube and produces a rectified grid current in substantially the same manner as does the radio frequency potential applied to the grid circuit when the tube is oscillating. By varying the potential of the 60 cycle current applied to the grid, as by varying the rheostat 10 in the primary circuit of transformer 7, a grid heating effect can be produced which is substantially the same as that of the high frequency current produced by the oscillator.

Because the grid of the oscillator tube requires an appreciable time to change its temperature, it is unnecessary that the grid circuit be energized with the 60 cycle heating current each time contact 21 on key 23 is closed. It is sufficient if power is applied to the grid circuit during actual pauses in signaling, when the tube is inactive for several seconds. Furthermore, it is undesirable that the grid heating current be applied oftener than is necessary because of the excessive wear and resultant rapid deterioration of contacts 27 and 28. To this end, relay 26 is preferably of the dash-pot type which operates only in response to a closure of upper key contact 21 in excess of a predetermined time. The relay must, however, be adapted to release quickly in order that the grid heating circuit may be disconnected following opening of contacts 21, before relay 20 operates to energize the tube for the production of oscillations. The dash-pot mechanism should, therefore, be designed to permit rapid motion in one direction, while restraining it in the other.

During intervals of rapid keying, while relay 26 remains unoperated, it has been found necessary for satisfactory operation to short out the secondary winding 8 of transformer 7 by means of auxiliary contacts 29 on relay 26. The reason for this is that when the tube is oscillating, more or less rectified current flows

in the grid circuit, whereas, during the short intervals when the key 23 is up and the tube is not oscillating no grid current flows. Were contacts 29 not provided, this rectified grid current would have to pass through secondary winding 8, which since it has a very high inductance, would oppose the building up of a current, and would result in a transient negative bias on the grid 3 which would of itself cause an undesirable shift in frequency. Furthermore, even were the artificial grid heating current applied each and every time that oscillations were interrupted, transient biasing voltages would be applied to the grid 3 because, in general, the rectified current artificially produced in the grid circuit is not the same as that resulting from the natural oscillations generated by the tube. By shorting out the winding 8 whenever signals are transmitted all such objectionable transient effects are prevented.

It has been found that the temperature of the grid is determined to a certain extent by the value of the rectified grid current, and therefore, the amplitude of the direct current flowing in the grid circuit is a rough measure of the heating effect being produced. To indicate the amplitude of the rectified grid current at all times, a direct current ammeter 11 is provided in the grid return path.

The circuit of Fig. 2 is similar to that of Fig. 1, except that it involves the use of a simpler relay structure for applying the grid heating current. In this case a source of current 33, which is shown as a direct current generator but may be an alternating current source, is adapted to be connected, through the armature and front contact 31 of relay 30, between the cathode 2 and grid 3 of tube 1. The keying circuit differs from that shown in Fig. 1 in that the key 23 has only one contact 22 which closes a circuit to operate the keying relay 20 and the grid heating control relay 30, simultaneously. When the key 23 is in normal position the armature of relay 30 lies against its back contact 32, thus connecting the negative terminal of source 33 to cathode 2 through grid ammeter 11, since the positive terminal of source 33 is permanently connected to the lower terminal of inductance 50. This completes a direct current circuit from the cathode to the grid, through source 33. When key 23 is closed, relay 20 applies operating potential to the anode from source 25, and relay 30 disconnects source 33 and completes another direct current circuit from the lower terminal of inductance 50 through front contact 31 and the armature of relay 30, through ammeter 11 to the cathode. The advantage of this arrangement over that disclosed in Fig. 1 is that relay 30, having a simple contact structure, may be of the vacuum relay type in which the contacts are enclosed in an evacuated space. Such relays are relatively durable and give satisfactory service

under continuous operation. As pointed out in connection with Fig. 1, however, it is not necessary to the successful operation of the system that relay 30 close the grid heating circuit during very short intervals between signals, and relay 30 may therefore be of the slow release type so that contact 32 is closed only after a predetermined non-signaling interval.

Fig. 3 depicts a modification of the circuit disclosed in Fig. 2 in which the source of anode potential 25 is used to supply both the anode current and the grid heating current. In this circuit the keying relay 38 is provided with a back contact 39. When signals are not being transmitted the armature of relay 38 is closed on its back contact 39, thus closing a circuit from the positive terminal of the source of anode potential 25 through a potentiometer comprising resistor 36 and 37 to the cathode 2. The resistance of the potentiometer is preferably chosen substantially equal to the average resistance of the anode circuit of the tube so that the current drawn from source 25 is uniform during both signaling and non-signaling intervals. Such a provision for maintaining a constant load on the source of anode potential is particularly useful to prevent sudden surges of current and voltage when the source of anode potential is a high impedance rectifying and filtering system excited by alternating current. The adjustable resistance 37 of the potentiometer is adjusted to apply such a potential to the grid 3 as will produce a desired grid heating effect. When signals are transmitted by pressing key 23, relays 34 and 38 operate simultaneously, relay 38 disconnecting the source of anode potential 25 from the potentiometer and connecting it, over front contact 40, to the anode circuit of the tube. At the same time, relay 34 closes its armature on contact 35 to short circuit the resistor 36 and provide a low impedance path from the lower terminal of inductance 50 through ammeter 11 to cathode 2.

Although not necessarily limited thereto, this invention is chiefly applicable to oscillators comprising high power tubes with water cooled anodes which are maintained at substantially uniform temperature during both operating and non-operating periods by the water circulating therethrough. In such tubes the cathode and anode temperatures are substantially uniform regardless of whether the tube is oscillating or not, and by providing the above described means for maintaining a uniform grid temperature, practically all variations in the inter-electrode capacities of the tubes may be eliminated.

I claim:

1. The method of increasing the frequency stability of a vacuum tube oscillator which comprises maintaining the grid of the tube at a substantially uniform temperature over

a period of time including oscillating and non-oscillating intervals.

2. The method of increasing the constancy of the frequency of a vacuum tube oscillator in a radio transmitter which comprises maintaining the grid of the tube at a substantially uniform temperature at all times.

3. In a radio transmitter comprising a vacuum tube oscillator with means for starting and stopping the cathode-anode current in said tube, the method of improving the frequency stability of the oscillator which comprises producing the same heating effect on the grid of the tube when the anode circuit of the tube is de-energized as when it is energized.

4. A radio transmitter comprising a vacuum tube oscillator having input and output radio frequency circuits coupled together, a source of cathode-anode current, a source of cathode-grid current, circuits for connecting said sources of current between said cathode and anode and cathode and grid, respectively, and keying means for simultaneously interrupting one circuit and closing the other.

5. In a radio telegraph transmitter, a vacuum tube oscillator, a source of anode potential therefor, keying means for controlling the application to the anode of said vacuum tube of potential from said source, a radio-frequency path between the cathode and grid and means in said path preventing the flow of current of less than radio frequency, a second path between said cathode and grid, a source of potential, and means responsive to said keying means for applying said potential to said grid over said second path during non-signaling periods.

6. In a radio transmitting system comprising a vacuum tube oscillator adapted to pass appreciable space current only when signals are being transmitted, the method of increasing the constancy of the frequency of operation which comprises energizing the cathode-grid circuit of said tube with current of a non-radiating frequency during non-signaling periods.

7. In a high frequency wave transmitting system a vacuum tube oscillator, input and output circuits therefor, a tuned frequency controlling circuit in said output circuit, means for energizing said output circuit whereby radio frequency oscillations may be generated by said tube, means for applying an electromotive force of less than radio frequency to said input circuit, and switching means whereby said electromotive force is applied to the input circuit of said tube only during periods when said output circuit is not energized.

8. In a radio transmitter an oscillator comprising a vacuum tube having a cathode, grid, and anode, a tuned circuit associated therewith and serving, in combination with the tube constants, to determine the frequency of

- oscillation, a source of current for energizing said cathode, a source of anode potential, a source of alternating current of sub-radio frequency, switching means for applying said anode potential to said anode, second switching means for applying such sub-radio frequency alternating current to the grid of said tube and keying means for simultaneously closing one of said switching means 10 and opening the other.
9. In a high frequency transmitting system comprising an oscillating vacuum tube having a cathode, grid and anode and adapted to pass appreciable space current only 15 when signals are being transmitted, the method of reducing transient variations in the frequency of operation which comprises energizing the cathode-grid circuit of said tube whereby a grid heating current is produced during non-signaling intervals.
10. In a high frequency oscillation generator, a vacuum tube having a cathode, grid and anode, a source of anode potential, switching means for applying said potential 20 to said anode for controlling the production of oscillations, and means for applying a positive potential to said grid during periods when the anode is de-energized, whereby the grid is maintained at substantially a constant temperature at all times.
11. In a high frequency oscillation generator, a vacuum tube containing a cathode adapted to emit electrons, an anode, and a grid positioned therebetween, an input circuit and an output circuit, a frequency determining circuit including as a determining element thereof the inherent capacity between said grid and the other electrodes, means whereby oscillations are applied between said grid and filament during the generation of oscillations, and means making said grid positive with respect to said cathode operative at least a portion of the time during which oscillations are not being generated.
12. In a high frequency carrier wave system, a source of oscillations, a vacuum tube having a cathode, grid, and anode, a frequency determining circuit comprising as an element thereof the capacity between the grid and other electrodes of said tube, means for impressing signal frequency potentials between the cathode and grid of said tube whereby a grid heating current results, and 35 means for preventing the application to said input circuit of said signal potentials and for simultaneously applying thereto a differently characterized potential capable of producing the same heating effect on said grid.
13. The method of improving the stability of operation of a three-electrode vacuum tube which consists in maintaining the grid of the tube at a substantially uniform temperature by applying supplemental heating current 40 thereto during non-operating intervals only.

14. A system comprising a three-electrode vacuum tube having a control electrode, input and output circuits for said vacuum tube, means for operating said system intermittently whereby the temperature of said control electrode would normally be caused to fluctuate, auxiliary heating means for said control electrode, said auxiliary heating means being operable to maintain the temperature of said control electrode during non-operating intervals of said tube, whereby the temperature of said control electrode is kept substantially constant during both operating and non-operating intervals.

In testimony whereof, I have hereunto set my hand.

HUGO ROMANDER.
